UNITED STATES PATENT OFFICE.

EDWARD J. McDONNELL, OF PITTSBURGH, PENNSYLVANIA, ASSIGNOR TO BLAW-KNOX COMPANY, OF PITTSBURGH, PENNSYLVANIA, A CORPORATION OF NEW JERSEY.

WATER-COOLED-DAMPER CONSTRUCTION.

Application filed September 20, 1922. Serial No. 589,379.

Figure 1 is a partial longitudinal section of an open hearth furnace provided with my improved water cooled dampers;

5 Figure 2 is a partial horizontal section; Figure 3 is a cross section showing the dampers in front elevation;

Figure 4 is a partial cross section similar to Figure 3 showing a modification;

10 Figure 5 is a top plan view, partly broken away, of the water cooled slot enclosure;

Figure 6 is a vertical longitudinal section of Figure 5;

Figure 7 is a vertical longitudinal section of one of the water cooled dampers;

15 Figures 8, 9 and 10 are detail views of damper parts hereinafter referred to;

Figures 11, 12 and 13 are detail views of the water cooled damper guides;

20 Figure 14 is an end view of the damper seat; and

Figure 15 is a detail view of the hanger frame for the damper.

My invention relates to the water cooling of open hearth structures, and particularly 25 to the water cooling of the dampers now used in the so-called "McKune" system, wherein the inlet for the air and gas at the inlet end of a reversing open hearth furnace is small compared with the outlet port area 30 at the opposite end for the outgoing gases.

The general damper system herein shown is not my invention, as the same was invented by George L. Danforth, Jr., of Chicago, Illinois.

35 My invention relates to the water cooling of these movable dampers, and relates to the water cooling of the damper itself, of the slot through which it slides, and the structure of the hood, seat, guides, etc.

40 In the drawings, 2 represents an open hearth furnace of the usual reversing type, and in the furnace shown 3 is the uptake leading to the gas inlet port and 4, 4 are uptakes leading to the air inlet ports at the side 45 of the covered gas port and rising over it.

Through the throat of the furnace, at each end, are arranged two water cooled dampers, indicated generally by the number 5. The throat is provided with two slots through 50 which these dampers slide, and over each slot is mounted a stationary enclosing hood 6 within which the damper may be raised. The preferred form of damper is illustrated in Figures 7 to 10 and consists preferably

of a surrounding hollow shell 7, preferably 55 of generally rectangular form with rounded corners, and which may be made of welded sheet or plate steel. The inner surface of this shell is preferably provided with ribs 8 which may be either separated or continuous 60 and are shown as made in separated sections at the sides and ends of the inner surface. These ribs enter suitable recesses in the lining brick and serve to hold it in place. The space within this shell is filled in with 65 fire brick, thus giving a fire brick damper with a surrounding metal cooling shell. The cooling water is preferably fed in through a pipe 9 passing down through a sleeve pipe 10, the pipe 9 having an extension 11 so 70 that the water is led down into one end of the hollow shell. The water, after circulating in the shell, flows out through the sleeve pipe 10 and another corresponding sleeve pipe 12. These sleeve pipes also serve 75 as hangers for the valve, they being secured to an upper cross bar 13 having a lifting yoke or ring 14 to which a wire rope may be attached for raising and lowering. On this lifting bar, 15 represents water connections, 16 being the inlet and 17 the outlet.

Within the hollow shell I also preferably enclose a high pressure perforated pipe 18 which is secured within the hollow shell by strips 19 and is connected with a high pressure supply pipe 20 leading up to the supply and exhaust fitting 21. If the hollow shell becomes clogged with mud or any sediment or collection, it may be blown out by supplying high pressure fluid, such as water or air, 90 to blow out the collection.

Each hood 6 is preferably suspended by hangers 22 from the structural work of the furnace, and comprises a metal shell having a cover 23 through which the hollow hangers and water connections extend. These shells are preferably lined with fire brick 24, and a packing of heat insulating material 25 is preferably provided between the refractory lining and the shell. In this manner, when the dampers are lifted, they will not be subjected to the chilling of the outside air, which would tend to cause the brick to crack and spall. At its lower end, each hood preferably rests on a water cooled slot casing 26 which is preferably inclined to suit the slope of the roof, as shown, for example, in Figure 3. Each of these hol-

low slot shells is preferably made of welded sheet or plate material, and in Figure 5, 27 represents the water inlet pipe and 28 the outlet pipe. In each of these shells I 5 also preferably provide a perforated blow-out pipe 29 having an inlet 30 for fluid under high pressure, this being generally similar to the corresponding pipe in the damper shell. I also preferably provide 10 water cooled damper guides 31 at the points shown in Figure 2, these preferably being of L-shape in cross section and of the form shown in detail in Figures 11 to 13, inclusive. They are also preferably made of 15 welded plates and have the usual inlet and outlet pipes, wash-out plugs, etc. In this construction, 32 is the water outlet pipe extending to near the closed top, and 33 is the inlet pipe.

20 I may also employ a water cooled seat for the damper, as shown at 34 in the modified form of Figure 4. This seat will protect the bottom portion of the water cooled damper from getting in direct contact with 25 refractory material having a very high temperature. It is of especial advantage where the water is muddy or contains sediment which may settle in the bottom of the damper cooler. In this water cooled 30 seat, which may be of welded plate material, 35 is the inlet pipe, 36 outlets, and 37 a high pressure perforated blow-off pipe through which fluid under considerable pressure may be fed when desired to clean out 35 sediment.

The advantages of my invention will be apparent to those skilled in the art, since an effective water cooling system is provided for movable dampers in reversing regenerative furnaces.

The dampers may slide in over the side instead of from the top; the line of movement may be at an angle to the vertical; the details may be varied; and other changes 45 may be made without departing from my invention.

I claim:—

1. In a reversing regenerative furnace, a 50 water cooled damper formed of refractory material with a water cooled shell surrounding the same, and means for insuring a forced circulation of the cooling water through said shell, comprising an inlet pipe 55 extending a substantial and fixed distance within said shell, substantially as described.

2. In a reversing regenerative furnace, a water cooled damper and a water cooled slot through which the damper moves, substantially as described.

60 3. In a reversing regenerative furnace, a water cooled damper and a refractory lined hood into which the same may be lifted through a slot in the furnace wall, substantially as described.

65 4. In a reversing regenerative furnace, a

water cooled damper, a hood projecting outward from the furnace wall, and a water cooled slot through the furnace wall, substantially as described.

5. In a reversing regenerative furnace, a 70 water cooled damper, and hollow hangers for supporting the damper having supply and exhaust pipes for supplying liquid to the water cooled portion of the damper, substantially as described. 75

6. In a reversing regenerative furnace, a water cooled damper having a water circulating passage therethrough, and a high pressure fluid supply pipe extending into and terminating in the circulating passage, 80 said high pressure fluid supply pipe constituting means by which sediment may be flushed out of the said circulating passage, substantially as described.

7. In a reversing regenerative furnace, a 85 hollow water cooled casing forming a water cooled slot through the furnace wall, and connections for supplying fluid under high pressure within said casing to wash out sediment, substantially as described. 90

8. A reversing regenerative furnace having a water cooled slot in its roof and a damper movable through the slot, substantially as described.

9. A reversing regenerative furnace having a water cooled slot in its roof and a water cooled damper movable through the slot, substantially as described.

10. In a reversing regenerative furnace, a water cooled damper having water cooled 100 guides, substantially as described.

11. In a reversing regenerative furnace, a water cooled damper, and water cooled guides therefor having seating portions for the damper, substantially as described. 105

12. In a reversing regenerative furnace, a water cooled damper and a water cooled seat therefor, substantially as described.

13. In a reversing regenerative furnace, a water cooled damper and water cooled 110 guides partly enclosing and guiding the same, substantially as described.

14. A reversing regenerative furnace having a water cooled slot in its roof, and a refractory lined hood resting on the water 115 cooled portion of the slot, substantially as described.

15. A water cooled damper having a surrounding water cooling frame with ribs or projections to hold the brickwork filling the 120 interior thereof, substantially as described.

16. A reversing regenerative furnace having slots in its throat portions and water cooled dampers movable through the slots, 125 substantially as described.

17. A reversing regenerative furnace having water cooled slots in its throat portions and water cooled dampers vertically movable therethrough, substantially as described. 130

18. A reversing regenerative furnace having water cooled slots in its throat portions and water cooled dampers vertically movable therethrough, said furnace having 5 refractory lined hoods into which the dampers may be drawn, substantially as described.
19. In a reversing regenerative furnace, a water cooled damper formed of refractory 10 material with a water cooled shell extending around the entire periphery thereof, and means for insuring a forced circulation of the cooling water throughout said shell, substantially as described.
20. In a reversing regenerative furnace, a 15 water cooled damper formed of refractory material with a water cooled shell surrounding the same, said shell having its inlet and outlet connections for the cooling water adjacent each other, substantially as 20 described.

In testimony whereof I have hereunto set my hand.

EDWARD J. McDONNELL.
